UNITED STATES PATENT OFFICE.

HERBERT P. GREEN, OF KANSAS CITY, MISSOURI.

REINFORCED CONCRETE CONSTRUCTION.

1,157,381.

Specification of Letters Patent. Patented Oct. 19, 1915.

Application filed June 19, 1911. Serial No. 634,007.

To all whom it may concern:

Be it known that I, HERBERT P. GREEN, a citizen of the United States, residing at Kansas City, in the county of Jackson and State of Missouri, have invented certain new and useful Improvements in Reinforced Concrete Construction; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to reinforced concrete construction and has for its object to provide a floor slab having concealed beams and girders, and wherein the space between said beams and girders is cored with tile, or the like, instead of being made of concrete, for the purpose of lightening the slab, thus allowing the manufacturer to reduce the amount of reinforcement, and the size of the supporting columns, and increase the clear height of the building, the number of floors possible, and the available floor space. In accomplishing this object, I have provided the improved details of structure hereinafter described and illustrated in the accompanying drawings, wherein the figure is a perspective view of a floor constructed according to my invention, the main part of the view showing the concrete broken away to disclose the beams and girders and slab cores.

Referring more in detail to the parts:—1 designates the columns, which may be of any ordinary construction. Extending between the columns 1 are direct girders 2, comprising a number of steel rods arranged in close proximity to each other and having the upturned sections 2' at the column positions to meet the reverse moments at such points. Extending diagonally between the columns 45 and diagonal girders 3, which are formed of the same material and in the same manner as the direct girders 2 and have the reverse moment sections 3' which cross the parts 2' above the columns.

Arranged in the spaces between the direct and diagonal girders are tiles 8, which are spaced from the direct and diagonal girder rods 2—3, to form channels 4—4'; the ends of the tiles facing the diagonal girders, being cut at an angle in order that the sides of such channels may be parallel. Between the

tiles 3 are reinforcing rods 5, called beams, which extend into the direct girders 2 and into the diagonal girders 3; the ends of the rods either terminating in the girders and being side lapped in the latter, or continuous into the next panel, as illustrated in the drawing.

6 designates a bed of concrete which fills the channels between the tiles and surrounds the direct girders, diagonal girders and beams to form a solid, compact slab having a smooth flooring surface and a flat ceiling.

In laying the slab, I use ordinary slab forms (not shown) which may be supported in any suitable manner and upon which the beam and girder rods and minor reinforcements are laid, together with the core tiles.

After the foundation parts have been placed, I pour the concrete, so that it flows into the spaces between the tiles and around the rods, so that when the fluid concrete has set, it will form a solid, substantial slab, and the separate parts will be united to form a solid unit.

It is readily apparent that by providing the diagonal girders, additional strength is afforded to withstand substantial weight, and that by filling the spaces between the direct girders and diagonal girders with the tile, the weight of the slab is reduced, while maintaining the required strength.

Having thus described my invention, what I claim as new therein and desire to secure by Letters Patent is:—

1. In concrete floor construction, the combination with supporting columns, of direct girder reinforcements supported by the columns, diagonal girder reinforcements also supported by the columns and forming triangular spaces with the direct girder reinforcement, spaced beam reinforcements within said triangular spaces and running parallel to the aforesaid direct girder reinforcements and resting on the latter, as well as on the said diagonal girder reinforcements, tiles between said spaced beam reinforcements, and concrete in the spaces between the tiles, forming integral beams and girders.

2. In reinforced concrete construction, a monolithic slab in combination with supporting columns, said slab consisting of concrete, tile and reinforcing rods, and comprising a flat ceiling and a flat floor surface with concealed girders and beams therebetween, the girders and beams being formed of the

- concrete and reinforcing rods between the tile arranged in spaced rows, the beams being between the sides of said spaced rows and the girders being between the ends of 5 said spaced rows, a portion of said girders being inclosing girders, forming the sides of inclosing parallelograms, within the slab, the supporting columns being at the corners thereof, the remaining portion of said girders intersecting at the center of the slab, and being diagonals within said inclosing parallelograms, the beams between said inclosing girders and said diagonals being 10 substantially perpendicular to an adjacent inclosing girder and at a smaller angle with a diagonal, the rods in the girders being continuous beyond the axis of the columns.
3. In a concrete floor construction the combination with a plurality of supports, of 15 reinforcement members laid thereover normally thereto with said respective reinforcement members disposed at right angles to one another to form substantially a rectangular panel between any four of said supports, diagonally disposed reinforcement members laid upon said supports subdividing said rectangular panel into four triangular panels, a plurality of rows of tiles placed 20 end to end laid within each of said triangular panels with the axes of said respective rows parallel to one another in each triangular panel and disposed normal to the axes of the reinforcement members disposed normal to said supports, said tiles in one row 25 spaced from those of another adjacent row permitting concrete to be bonded between the respective rows thereof in each of said

triangular panels forming beams within the main rectangular panel which are normal to the reinforcement members bounding said 40 rectangular panel and directed toward the middle thereof, and a plurality of reinforcing members laid between said tiles and molded into the concrete beam so formed.

4. In a concrete panel floor construction 45 a plurality of supports, and a monolithic concrete floor supported thereon, said supports disposed to form the bounding corners of integrally connected rectangular floor panel sections, each panel section divided 50 geometrically into four triangular panel sections, reinforcement members laid upon said supports with their axes disposed coincident with the boundary lines of said triangular panel sections, a series of rows of tiles placed 55 within each triangular panel section, said rows spaced one from another to permit bonding of the concrete therebetween, and all of said rows directed toward the middle of the rectangular floor panel section, the innermost tiles of the rows of tiles of each 60 triangular section having one edge cut away parallel to the boundaries of the triangular panel sections, and reinforcement members 65 laid between said respective rows of tiles and bonded into the concrete molded into the structure.

In testimony whereof I affix my signature in presence of two witnesses.
